Fig. 2

Fig. 5

FIG. 1 is a top plan view of a floor mat showing my new design,

FIG. 2 is a section taken on a plane indicated by the line 2—2 in FIG. 1.

FIG. 3 is an enlarged fragmentary cross-sectional view taken from the left side of FIG. 2;

FIG. 4 is an enlarged detail view taken from the lower left corner of FIG. 1; and

FIG. 5 is an enlarged fragmentary view taken from the left side of FIG. 1.

The drawing is shaded to show contrast.

I claim:

The ornamental design for a floor mat, substantially as shown and described.
